Patented July 6, 1920.

Julius Engelbrecht INVENTOR

C. M. Wallen

UNITED STATES PATENT OFFICE.

JULIUS ENGELBRECHT, OF BOONE, COLORADO.

CARRYING-TRUCK.

1,345,667.

Specification of Letters Patent.

Patented July 6, 1920.

Application filed March 5, 1919. Serial No. 280,832.

To all whom it may concern:

Be it known that I, JULIUS ENGELBRECHT, a citizen of the United States, residing at Boone, in the county of Pueblo and State of Colorado, have invented a new and useful Carrying-Truck, of which the following is a specification.

It is the object of this invention to provide a novel means whereby a ditcher or like implement may be raised or lowered, either to facilitate transportation or to vary the depth to which the plow portion of the ditcher penetrates the soil.

In the drawings:—Figure 1 discloses in side elevation, a device wherein the invention has been embodied, parts being broken away; and Fig. 2 is a top plan of the device depicted in Fig. 1, parts being broken away.

The ditcher or plow wherewith the truck hereinafter described is used, may be variously constructed. It may comprise a point 1 embodying a standard 50 secured in the angle defined by diverging mold boards 2 prolonged to form an arm 3 terminating in a bearing 4. A beam like shoe 13 is attached by braces 14 to the mold boards 2. A drum 15 is journaled on the shoe 13 and is controlled by any suitable means shown at 25.

The invention includes a truck, embodying an upright post 5, whereon the bearing 4 of the arm 3 is vertically slidable. The post 5 carries an axle 26 provided with ground wheels 18. Converging braces 8 and 9 extend from the post 5 and merge into a head 27. The braces 8 and 9 and the head 27 may be alluded to as a forwardly presented frame carried by the post 5. A hanger 10 is mounted on the head 27 and serves as a guide and support for a draft element 11, which may be in the form of a chain having its rear end attached at 12 to the plow.

A bracket 17 is mounted on the upper end 45 of the post 5 and carries a pulley 7. A

bracket 28 is attached to the arm 3 near to the post 5 and supports a pulley 6. One end of a flexible element 16 is attached at 29 to the bracket 17, the flexible element being formed into a loop 30 receiving the 50 pulley 6, and being extended across the pulley 7. From the pulley 7, the flexible element 16 extends downwardly and rearwardly and is connected with the winding device or drum 15. 55

It will be obvious that when the drum 15 is actuated by the means 25, the flexible element 16 will be wound upon the drum, the loop 30 will be shortened, and the plow will be elevated, the bearing 4 sliding on the 60 post 5 of the truck. The operation described adjusts the penetration of the plow point 1 into the soil, and permits the point to be raised well above the soil for transportation. 65

I claim:—

1. In a device of the class described, a truck embodying a post; a plow having an arm slidable vertically upon the post; an idler on the post; an idler on the arm; a winding device on the plow; and a flexible element formed into a depending loop receiving the idler on the arm, the flexible element being trained across the idler on the post, one end of the flexible element being 75 fixed with respect to the post, the other end of the flexible element being assembled with the winding device. 70

2. A structure of the class described, constructed as set forth in claim 1, and further characterized by the provision of a forwardly presented frame carried by the post; a guide on the frame; and a draft element extended through the guide and connected at its rear end to the plow. 80

JULIUS ENGELBRECHT.
